UNITED STATES PATENT OFFICE.

STANLEY W. FINCH, OF WASHINGTON, DISTRICT OF COLUMBIA.

DESIGN FOR A FRAME OR BODY FOR BICYCLE-SKATES.

SPECIFICATION forming part of Design No. 28,753, dated May 31, 1898.

Application filed March 11, 1898. Serial No. 673,539. Term of patent 14 years.

To all whom it may concern:

Be it known that I, STANLEY W. FINCH, a citizen of the United States, residing at Washington, in the District of Columbia, have invented and produced a new and original Design for a Frame for Bicycle-Skates, of which the following is a specification, reference being had to the accompanying drawings, forming part thereof.

10 Figure 1 is a side view of the frame of the bicycle-skate, showing my new design. Fig. 2 is a plan view thereof, and Fig. 3 a front view.

As shown in the drawings, the leading or 15 material feature of my design consists in the side portions A A, arranged upon the same horizontal plane and approximately parallel for the greater part of their length, but are brought quite close together at B and bent 20 upward at C and secured together at D. At D is an upright or slightly-inclined part E.

The two side portions A A are connected together by depending straps F, which drop below the level of the side pieces A A. G is

the foot-plate, resting upon said depending straps F.

The rear extremities B of the side pieces are slotted, as shown at H.

At the front extremities of the parts A, where they are secured together at D, is arranged the front fork I, having the side pieces J J, bent at the top in a gradual curve at K and secured together by the cross part L, part way down from the top. The lower extremities of the sides J J are slotted, as shown at M.

Having now described my invention, what I claim as new, and desire to secure by Letters Patent, is—

The design for the body of a bicycle-skate, 40 substantially as shown and described.

This specification signed and witnessed this 11th day of March, 1898.

STANLEY W. FINCH.
